(57) **CLAIM**

The ornamental design for a food slicer, as shown and described.

DESCRIPTION

FIG. 1 is a top perspective view of a food slicer;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken dashed and dashed-dot lines show various portions and other elements in the Figures for the purpose of illustrating unclaimed portions and form no part of the claimed design.

1 Claim, 4 Drawing Sheets
